UNITED STATES PATENT OFFICE

FREDERICK A. SCHROEDER, OF ROCHELLE PARK, AND ALBERT E. TWIST, OF RUTHERFORD, NEW JERSEY, ASSIGNEES TO RAYMOND CONCRETE PILE COMPANY, OF NEW YORK, N. Y., A CORPORATION OF NEW JERSEY

PILE SHELL

Application filed January 15, 1932. Serial No. 586,800.

This invention pertains to shells for concrete piles, with special reference to shells adapted for service in soils containing considerable abrasive material. Under such conditions it has often been found desirable to use a shell having outer casing and inner lining of sheet metal with the space between the metal sheets filled with non-metallic reinforcing material usually in the form of cement or concrete.

Each shell for convenience, is usually made up of a stack of comparatively short shell sections one above the other. The assembled shell is carried into the ground by a driving core which is then removed and the shell afterwards filled with concrete to become an integral part of the finished pile structure.

A shell of the above general type is shown in Patent No. 1,839,359, which will issue on January 5, 1932 to Maxwell M. Upson and Herman R. Smith.

In that patent the outer casing is of corrugated metal while the inner lining is of plain metal. In use of that shell under some conditions, for instance if a number of shells are driven close together before filling, the pressure of the earth may slightly distort the thin lining out of contact with the shell filler at the end of a shell section. If that condition arises at the upper end of a section the concrete falling into the shell during the filling operation may get behind the lining and increase the distortion thereby cutting off the continuity of the concrete and impairing the quality of the finished pile.

One object of the present invention is to overcome the above difficulty by sufficiently stiffening the inner lining, as by corrugating it, so it will be able to better resist distortion.

Another object is to provide a reinforced shell having a corrugated surface in contact with the driving core whereby a corrugated driving core may be used in case it is desired to use the shell in nontapered form, and whereby in driving tapered shells the driving core may more readily be freed from the grip of the shell.

Further and other objects and advantages will be apparent from the specification and claims, and from the accompanying drawings which illustrate what is now considered the preferred embodiment of the invention.

Fig. 1 shows a shell in cross-section, after driving and before withdrawal of the driving core.

Fig. 2 is an enlarged view mostly in section of a shell section.

Fig. 3 is a fragmentary view of a modified form of the invention.

Figs. 4 and 5 show modified forms of the invention, particularly the method of coupling the shell sections together.

Fig. 6 shows another form of the invention.

Fig. 7 is a cross-section on line 7—7 of Fig. 6.

Referring to Figs. 1 and 2, each shell section comprises a plain outer casing 10 of thin material, a corrugated inner lining 12 of thin material, and a filler 14 between casing and lining. The casing and lining are usually of sheet steel, and the filler is usually of non-metallic, waterproof material such as cement or concrete. The filler is usually inserted in liquid form, such as grout, which readily completely fills the spaces between casing and lining, and then hardens to bind the component parts of the shell section into a unitary structure.

Each casing is extended as at 16 to form a socket for receiving an end of the next adjoining section when the sections are assembled for driving on a core 18, as in Fig. 1, in which the core is tapered and the shell sections shaped accordingly.

In Fig. 3 the outer diameter of lining 12 is somewhat less than the inner diameter of casing 10, thus providing clearance as at 22 between casing and lining at all points, the clearance space being, of course, filled with filler.

In the modification of Fig. 4, casing 10 rises no higher than the top of lining 12, the coupling socket being formed by a helically corrugated sleeve 24 having its lower end 26 welded to the upper end of casing 10.

The casing of the lower end of the next

higher shell section is helically corrugated as at 28 to screw into socket 24. In this modification the metal casing and lining are spaced well apart, therefore filler 14 may 5 extend well down into coupling socket 24. In the embodiment of Fig. 5, however, the threaded lower end 28 of the casing is in contact with lining 12, and the socket is formed not by welding on a socket 24 but by 10 threading, as at 30, the upwardly extending end of the casing 10. Thus this joint has three thicknesses of metal in close engagement.

In the modification of Figs. 6 and 7, vertical reinforcing rods 32 are inserted in the non-metallic filler between casing and lining, and the joint between shell sections is of somewhat different type. An upwardly projecting ring 34 of plain metal is welded 20 to the upper end of the lower casing 10, while the lower ends of casing and lining of the upper shell section are pinched together as at 36 and preferably welded to each other.

25 Closure of the lower ends of shell sections as in Figs. 5 and 6 prevents flow of grout therethrough and thereby facilitates the filling operation.

It is to be understood that the invention is 30 not limited to the specific embodiment herein illustrated and described, but may be used in other ways without departure from its spirit as defined by the following claims.

1. As an article of manufacture, a permanent pile shell for driving and subsequent filling, comprising in combination, an outer casing of thin material, an inner lining of corrugated material, and a filler of non-metallic reinforcing material between said 35 casing and said lining.

2. As an article of manufacture, a pile shell for driving on a removable core and for filling after removal of the core, comprising in combination, an outer metallic casing of thin material, a corrugated metallic lining adapted to contact with the core during 45 driving and a reinforcing filler of non-metallic material between said casing and said lining.

50 3. The invention set forth in claim 2 in which substantially vertical reinforcing rods are imbedded in said filler.

4. As an article of manufacture, a pile shell for driving on a removable core and 55 for filling after removal of the core, comprising in combination, an outer metallic casing of thin material, a corrugated metallic lining within said casing in contact therewith, and a filler of non-metallic material between 60 the casing and the corrugations of the lining.

5. A permanent pile shell comprising a plurality of sections adapted to enclose a core by which the shell is driven, each of said 65 sections comprising an outer plain casing,

an inner corrugated lining and a non-metallic reinforcing filler between said casing and said lining, said casings being provided at their ends with helically corrugated extensions whereby an end of each section may be screwed into the adjacent end of the next section, in order to couple said sections together. 70

6. A permanent pile shell comprising a plurality of sections adapted to enclose a core by which the shell is driven, each of said sections comprising an outer plain casing, an inner corrugated lining and a non-metallic reinforcing filler between said casing and said lining, each of said sections having at one end a socket formed by an extension of said casing and having at its other end an extension formed by extensions of said casing and said lining in contact with each other, the extensions at both ends of the section being helically corrugated whereby the ends of adjoining sections may be screwed together to form the pile shell. 75 80

7. The invention set forth in claim 6 in which said other extension is provided with non-metallic filler between said casing and said lining. 90

8. As an article of manufacture, a permanent pile shell for driving and subsequent filling, comprising in combination, an outer casing of thin material, an inner lining of corrugated material, and a filler of non-metallic reinforcing material between said casing and said lining, said casing and lining being joined together at their ends to provide a closure for the space occupied by the 95 filler. 100

In testimony whereof we hereto affix our signatures.

FREDERICK A. SCHROEDER.
ALBERT E. TWIST.
